METHOD OF AND MEANS FOR PRODUCING REED FABRIC AND THE LIKE

Filed June 5, 1920

UNITED STATES PATENT OFFICE.

MARSHALL BURNS LLOYD, OF MENOMINEE, MICHIGAN, ASSIGNOR, BY MESNE ASSIGNMENTS, TO HEYWOOD-WAKEFIELD COMPANY, OF BOSTON, MASSACHUSETTS, A CORPORATION OF MASSACHUSETTS.

METHOD OF AND MEANS FOR PRODUCING REED FABRIC AND THE LIKE.

Application filed June 5, 1920. Serial No. 386,832.

To all whom it may concern:

Be it known that I, MARSHALL BURNS LLOYD, a citizen of the United States, and a resident of Menominee, county of Menominee, and State of Michigan, have invented a certain new, useful, and Improved Method of and Means for Producing Reed Fabric and the like, of which the following is a specification.

10 My invention relates generally to the production of reed fabric which is composed of spaced relatively rigid stake members around which relatively flexible filler strands are intertwined, and my invention embraces both 15 the natural reed and the so-called fibre reed.

It is an object of my invention to provide a method and means whereby fabric of the above character can be produced with great rapidity and at low cost.

20 Another object of my invention is to provide a method for the production of reed fabric, which shall be practicable by unskilled labor, and to provide mechanism of simple and durable construction wherewith 25 to practice the method. It is also an object of my invention to provide a method and apparatus wherewith fabric can be produced without subjecting either the stakes or filler strands to strains or forces likely to split 30 or injure them.

My invention consists generally in the steps, acts, and stated sequence thereof, and in the means for performing such acts, whereby the above named objects, together 35 with others that will appear hereinafter, are attainable; and my invention will be more readily understood by reference to the accompanying drawings which illustrate what I consider, at the present time, to be the 40 preferable mode of procedure and suitable mechanism for practising the invention.

In said drawings:

Fig. 1 is a side elevation of apparatus embodying the invention.

45 Fig. 2 is an end elevation thereof.

Fig. 3 is an enlarged view taken substantially on the line A of Fig. 1.

Fig. 4 is a detail sectional view substantially on the line X—X of Fig. 1.

50 Fig. 5 is a detail sectional view substantially on the line Y—Y of Fig. 1.

Fig. 6 is a view of a piece of filler strand in the form in which I prefer to prepare it when using fibre reed.

Fig. 7 is a detail sectional view illustrating 55 means for shaping reed filler strands.

Fig. 8 is a detail sectional view illustrating means for shaping the fibre reed filler strands; and

Fig. 9 is a detail fragmentary view on the 60 line Z of Fig. 1.

As before stated, reed fabrics are produced from two separate materials, one being the natural reed and the other fibre reed. While the general characteristics of these materials 65 are similar, they vary in some respects. The natural reed is less pliable than the fibre reed and the danger of cracking or splitting is greater. I propose to handle the natural reed and the fibre reed in the same general 70 way but to modify the method slightly, better to conform to the characteristics of the respective materials. In the production of reed fabric under my method I provide means for holding a large number of stakes 75 in desired spaced relation, and for moving certain of the stakes away from the plane of the others at which time I insert a previously conditioned or shaped filler strand into the shed thus formed.

80 The conditioning of the filler strand consists in imparting to it an undulatory form such as will enable it to conform to the stakes, i. e. pass over and under desired stakes without placing it under tension or in 85 anywise straining the stakes or the filler strands. Thereafter the group of stakes moved from their initial plane in one direction are moved in the opposite direction past their initial plane thus forming a shed such 90 that when another filler strand is dropped into place it will pass down the opposite sides of the stakes with respect to the previously inserted filler strand. By thus conditioning the filler strand, it becomes possible successfully to form at one operation a fabric of 95 extremely great width and without danger of kinking, breaking, injuring or splitting either the stakes or the filler strands.

Having thus described the general mode 100 of procedure I shall describe in detail the herein disclosed mechanism.

Referring to Fig. 7, 2 is a lower die member and 3 an upper die member which are formed with undulatory face portions 2' and 3' respectively. Means (not shown) are provided for separating the upper and lower die members and when in their separated condition a filler strand 4 is inserted and when the die members are brought together the initially straight filler strand is given an undulatory form. The die mechanism shown in Fig. 7 is of the form that I prefer to use when conditioning the natural reed filler strands, i. e. the face of the dies is provided with gentle curves so that the filler strand can be formed without danger of splitting it. The general undulatory form of the filler strand is probably better shown in the enlarged view—Fig. 3. In Fig. 8 I have shown an arrangement similar to Fig. 7 except that the die surfaces are formed with somewhat more abrupt angles. This is the form that I prefer to use when shaping a fibre reed filler strand for the reason that fibre reed is considerably more pliable and must be given a somewhat more definite angular shape in order to maintain its crimped form. The filler strand resulting from the action of the die arrangement shown in Fig. 8 is depicted in Fig. 6.

Referring now particularly to Figs. 1 and 2, 5 and 6 represent end frame members which are cross-connected and held in desired spaced relation by the bar 7. The bar 7, as is probably best shown in Fig. 4, has an upstanding rearward portion 7' and slightly spaced therefrom will be found a flap member 8 which is swingably secured to the lower part of the member 7 as by means of hinges 9. The stakes 10 and 10' of the fabric are held in desired spaced relation by being clamped between the flap member 8 and the rearward upstanding portion 7' of the member 7, their lower ends resting upon the ledge 7''. In order tightly to grip and hold the stakes, I have provided a number of thumb screws 11.

In the present instance, it is desired to have the filler strand pass over and under alternate stakes and I shall describe the method and apparatus with such a fabric in view, but I wish it to be understood that this is by way of illustration and not by way of limitation. Alternate stakes 10' project upwardly beyond the intermediate stakes 10 and their upper ends are clamped against a bar 12 by means of the flap member 13 which is secured thereto by means of the hinges 14. Thumb screws 15 are provided for tightening the flap 13. The bar 12 is attached to the end members 16 and 17, respectively, that upstand from and are pivotally secured to the frame members 5 and 6, as by means of the pivots 18 and 19 respectively. Thus the bar 12 can be swung

from one side to the other of the central vertical position, and when thus swung acts to move alternate stakes away from the initial or vertical plane (as is shown in Fig. 2). At this time one of the previously crimped or shaped filler strands can be inserted by simply dropping it in place in the shed thus formed. In order tightly to pack the filler strand, i. e. move it into intimate relation to the preformed fabric, I prefer to provide the packing bar 21 which is vertically slideable upon the end standards 20 and 22, respectively. This may be moved vertically to accomplish this function.

In order to "break" the stakes, i. e. cause them to bend properly when the frame or bar 12 is swung from one side to the other I prefer to provide a longitudinal bar member 23 which is provided with a longitudinal slot 24 through which the stakes project. This bar is slideable upon the standards 20 and 22 and may be fixed thereto by means of the set screws 24. This bar hereinafter termed a "breaker bar" may be moved upwardly as the weave progresses.

In order to limit the swinging movement of the standards 16 and 17, I prefer to provide the frame members 5 and 6 with upstanding portions having spaced stop portions 25 and 26 (see Fig. 2).

With the mechanism herein shown a large expanse of fabric can be quickly and easily produced. So soon as it is completed, members 8 and 13 can be released and the entire fabric removed, at which time the apparatus is ready to receive another set of stakes for the production of another fabric, as hereinbefore described.

I claim:

1. An apparatus for producing reed fabric and the like embodying therein means for gripping the ends of a plurality of stakes thereby holding them in spaced relation, means for gripping the opposite ends of desired stakes, said last mentioned gripping means being mounted for swinging movement, and means for "breaking" a group of stakes that are swung by said swingable means.

2. An apparatus for producing reed fabric and the like embodying therein means for gripping the ends of a plurality of stakes thereby holding them in spaced relation, means for gripping the opposite ends of desired stakes, said last mentioned gripping means being mounted for swinging movement, means for "breaking" a group of stakes that are swung by said swingable means, and means for adjustably holding said "breaker" means.

3. An apparatus for producing reed fabric and the like embodying therein means for gripping the ends of a plurality of stakes thereby holding them in spaced rela-

tion, means for gripping the opposite ends of desired stakes, said last mentioned gripping means being mounted for swinging movement, means for "breaking" a group of stakes that are swung by said swingable means, and a packer bar arranged for reciprocatory movement.

4. An apparatus for producing reed fabric and the like embodying therein means for gripping the ends of a plurality of stakes thereby holding them in spaced relation, means for gripping the opposite ends of desired stakes, said last mentioned gripping means being mounted for swinging movement, an adjustable "breaker" bar for "breaking" a group of stakes that are swung by said swingable means, and a packer bar arranged for reciprocatory movement.

5. An apparatus for producing reed fabric and the like embodying therein means for gripping the ends of a plurality of stakes thereby holding them in spaced relation, means for gripping the opposite ends

of desired stakes, said last mentioned gripping means being mounted for swinging movement, and means for "breaking" a group of stakes that are swung by said swingable means, said gripping means comprising a bar, a flap hinged thereto, and means for moving said flap in clamping direction.

6. An apparatus for producing reed fabric and the like embodying therein means for gripping the ends of a plurality of stakes thereby holding them in spaced relation, means for gripping the opposite ends of desired stakes, said last mentioned gripping means being mounted for swinging movement, and means for "breaking" a group of stakes that are swung by said swingable means, said "breaker" means being formed of a bar having a slot adapted to accommodate the stakes.

In testimony whereof, I have hereunto set my hand, this 8th day of April, 1920.

MARSHALL BURNS LLOYD.
